INVENTOR

WILLIAM H. CLOUD

BY
Richard J. Cook
ATTORNEY

UNITED STATES PATENT OFFICE.

WILLIAM H. CLOUD, OF SEATTLE, WASHINGTON.

CHANGE-DISPENSER.

1,360,367.

Specification of Letters Patent. Patented Nov. 30, 1920.

Application filed December 18, 1917, Serial No. 207,800. Renewed May 3, 1920. Serial No. 378,656.

To all whom it may concern:

Be it known that I, WILLIAM H. CLOUD, a citizen of the United States, residing at Seattle, in the county of King and State of Washington, have invented a new and useful Improvement in Change-Dispensers, of which the following is a specification.

This invention relates to improvements in devices for facilitating the handling of small articles, as for instance the handling of change at a cashier's desk or counter, and the object of this improvement is to provide a cheap and simple device on which small articles, as small pieces of change, or small metallic devices, may be placed, and from which they may quickly and easily be transferred into a person's hand without being picked up with the fingers.

In a general way the device comprises a pedestal or base that is adapted to rest on any plane surface, as a desk or table, and that supports a concave receptacle in such manner that the receptacle may be tilted sidewise by a simple pressure of the hand to discharge the contents thereof into the hand.

The invention consists in the novel construction, adaptation and combination of parts of a change dispensing device, as will be more clearly hereinafter described and claimed.

In the accompanying drawings, Figure 1 is a view in vertical section of a device constructed in accordance with this invention as it may appear when in a normal upright position; Fig. 2 is a view in elevation of the same as it may appear when it is tilted into a suitable position for discharging its contents; Fig. 3 is a view in vertical section of a modified form of the device and Figs. 4 and 5 are views in elevation of two other modified forms of the device.

This device is exceptionally well adapted for use as a change dispenser for small coins, and will be referred to in this capacity in some places in the following description, but it will be understood that it is not limited to this use but is equally well adapted for handling any small articles that are inconvenient to pick up when placed on a plane surface.

Referring to the drawings throughout which like reference numerals designate like parts, the numeral 7, Figs. 1 and 2, designates a pedestal or base having a centrally

disposed upright support 8 that is provided on its top end with an upwardly directed annular rim 9 and is adapted to support a tiltable holder that is designated in a general way by the numeral 10.

The holder 10 is provided on its top side with a concave receptacle 11 that is preferably constructed of sheet metal and is shaped so that an annular inclined rim 12 is formed around the outer edge thereof for the contents to slide over as they are discharged from such receptacle.

Extending downwardly from the rim 12 and integral therewith is an annular curved portion 13 that projects outwardly beyond the limits of the perimeter of the rim 12 at its bottom edge and serves as a hand engaging element by which the holder may be tilted.

The bottom side of the receptacle 11 is provided with a centrally disposed fixed disk 14 that fits loosely within the rim 9 and cooperates therewith to form a relatively stable support for the holder and a universal joint on which such holder may be tilted in any direction.

The disk 14 and rim 9 are of large enough diameter so that they form a sufficiently large support to prevent the holder from tilting under the weight of articles that may be placed therein in such a position as to unbalance the holder.

The disk 14 and receptacle 9 are disposed within a cylindrical casing 15 that is secured to the receptacle 11 and projects downwardly therefrom.

The bottom edges of the casing 15 engage with the support 8 and limit the tilting movement of the holder and such bottom edges are preferably bent inward as at 16 to prevent the holder being removed from the base portion.

When used as a coin dispenser the device may be set on a cashier's desk or counter over which change, as metallic coin 17, is returned to the public. When change is due a customer, the cashier may place the change in the receptacle 11 and the customer may place the edge of his hand against the curved periphery 13 with the palm upturned and extended and exert a pressure to tilt the holder 10 into an inclined position as shown in Fig. 2, so that the change will be discharged over the rim 12 into his hand.

As soon as the pressure on the holder is released it will immediately resume the upright position shown in Fig. 1.

The device will operate in substantially 5 the same manner when used for dispensing any other small article as when used for dispensing coins.

Fig. 3 discloses a modified form of the invention wherein is provided a pedestal 20 having a centrally arranged upright support 21 that is provided near its top end with an enlarged portion 22 around which extends an annular flange 23 that has an upturned outer edge or rim 24. 10 15 25 is a concave tray or receptacle that is supported upon a hemispherical shell 26 the lower edge of which rests on the flange 23. The rim of the tray 25 is preferably bent downwardly or offset as shown at 27. 20 28 is a cylindrical member having a transverse wall 29 that is provided with a central aperture having a downturned peripheral edge 30 that is adapted to hook over the upturned edge 24 of the flange 23 25 whereby the member 28 is supported.

The upper edge of the member 28 is turned or bent in, as shown at 32, and the lower portion of such member is provided with a curved element 33 against which the 30 hand may be placed to tilt the device.

The chief advantage of the device shown in Fig. 3 is that the sides of the member 28 project above the edges of the tray or receptacle 25 when the device is in its normal upright position and thereby prevent the coins from accidentally falling over the edge of such coin receptacle when they are placed therein.

To remove change or other articles from 40 the receptacle 25, the hand is placed against the portion 33 in an open position with the palm upward and a pressure is exerted to tilt the several parts into the position shown by broken lines, so that the contents of the 45 tray 25 will be discharged into the hand.

It is obvious that when the member 28 is tilted, the inwardly turned top edge 32 on the side toward which the member is inclined will first engage with the depressed 50 peripheral portion 27 of the receptacle and will then carry the receptacle downwardly along with it into the position shown by broken lines.

Fig. 4 illustrates a concave receptacle 55 35, having two spaced apart bearing pins 36

projecting from each side thereof and supported in slots 37 in two oppositely disposed standards 38, only one of which is shown.

The bottom of the receptacle 35 is provided with a downwardly extending member 39 against which the ends of the fingers may be placed to tilt the receptacle into the position shown by broken lines, and cause the contents thereof to be discharged into the hand. 60 65

In the construction shown in Fig. 4 the spaced apart bearing pins will prevent the weight of the contents from tilting the receptacle and will cause such device to normally assume an upright position after it 70 has been tilted.

Fig. 5 shows a coin receptacle 40 supported by a standard 41 that is mounted on a solid base member 42 having a rounded bottom 43. 75

The base 42 is of larger diameter than the coin receptacle 40 and has a flat top side 44 on which the hand may be placed to tilt the device into a discharging position as shown by broken lines. 80

It is obvious that other variations in the form of this device which fall within the scope of the appended claims will suggest themselves to those skilled in the mechanical arts. 85

What I claim, and desire to protect by Letters Patent, is:

A device of the class described comprising a pedestal that is provided at its top end with an upwardly directed circular rim 90 of relatively small diameter, a concave receptacle, a disk secured to the bottom side of said receptacle in the center thereof and adapted to fit within said rim, downwardly projecting curved sides on said receptacle, 95 said sides forming hand engaging elements, and a downwardly projecting casing on said receptacle and surrounding the top end of said pedestal to limit the angle through which said receptacle may be tilted, the bottom edges of said casing being turned inwardly to prevent the removal of said receptacle from said pedestal. 100

Signed by me at Seattle, Washington, this 6th day of December, 1917.

WILLIAM H. CLOUD.
